DOOR CONSTRUCTION

George R. Treptow, Chicago, Ill., assignor, by
mesne assignments, to The Youngstown Steel
Door Company, Cleveland, Ohio, a corporation
of Ohio

Application August 15, 1934, Serial No. 739,893

10 Claims. (Cl. 20—22)

This invention relates to lift doors and concerns itself more particularly with means for frictionally supporting said doors and for improving the weather condition adjacent the lower horizontal margin thereof.

It has been customary in the past where doors of the lift type have been utilized upon the sides of railway freight cars to establish frictional engagement between the lower edges of said doors and a supporting track therefor. By this engagement between the door and the supporting track in the lowered or normal position of the door, the lift and supporting fixtures are relieved of the weight of the door which is carried directly by the track. The frictional engagement has customarily been effected between the lower edge of the door and the tread of the track which, heretofore, has been disposed in a single plane. Accordingly, a wide surface contact between the door and the track was obtained. It was found, however, in the actual employment of doors of the lift type on railway cars that cinders and other foreign matter sometimes accumulated upon the track so that when the door was lowered the bottom edge thereof would be seated upon the cinders or other foreign substances rather than in direct engagement with the tread of the track. A space was thus formed between the tread of the track and the bottom edge of the door through which dust, cinders and rain might blow into the car through the door opening controlled by the door. In these former constructions, moreover, it sometimes occurred that air currents would force cinders, dust and the like upwardly in the space between the inner surface of the door and the threshold plate or floor in the door opening and thence into the car through the door opening.

This invention, consequently, has for its main object the improvement upon the conditions set forth above and encountered in constructions embodying doors of the lift type. This improvement contemplates a reduction in area of contact between the bottom edge of the door and the track and provides a construction in the door opening of the car by means of which the ingress of cinders, dust and the like into the car around the lower edge of the door is precluded.

The foregoing object, together with others which will more clearly appear as the description of the instant invention proceeds, are accomplished by means of the novel structure and combination of parts hereinafter described and more particularly pointed out and defined in the appended claims.

In the accompanying drawings forming part of this specification

Figure 1 is an elevation of a railway freight car utilizing lift doors and embodying one form of the invention;

Figure 2 is a vertical section taken on line 2—2 of Figure 1, illustrating the door in its lowered or normal position;

Figure 3 is a vertical section similar to Figure 2, showing the door in elevated position;

Figure 4 is a vertical section taken on line 4—4 of Figure 1; and

Figures 5, 6 and 7 are views similar to Figure 2, showing further embodiments of the invention.

Referring, first, to the embodiment of the invention illustrated in Figures 1 to 4, inclusive, of the drawings, the numeral 10 designates a portion of the siding of a railway car. This siding is provided with the customary door opening adapted to be controlled by means of a door 11. The door is of the type known as lift door and is supported upon the car side by means of a track 12 secured to the side sill 13 by means of a plurality of brackets 14. As clearly illustrated in Figure 2 of the drawings, the door 11 in its lowered or normal position is disposed in frictional engagement with the track.

Lift mechanism is provided upon the door by means of which said frictional engagement between the door and the track may be broken and the door elevated above the track for support upon antifriction means incorporated in the lift mechanism. One form of lift mechanism which may be utilized is shown in Figures 1 to 3 of the drawings. This form embodies a plurality of roller retainers 15 and 16. These retainers carry pins 17 upon which rollers 18 and 19 are mounted. Preferably, roller bearings 20 are interposed between the hubs of the rollers and the pins 17. The roller retainers are provided with pairs of trunnions 21 and 22 disposed in offset relationship to the pins 17 adapted to be journaled within cover plates 23 and 24 and in the lower marginal portion of the door. This marginal portion of the door, as clearly appears from Figure 2 of the drawings, embodies a reinforcing angle member 25, the leg 26 of which is vertically disposed and the leg 27 of which is positioned horizontally. The horizontal leg 27 is coped as indicated at 28 in order to permit the rollers 18 and 19 to extend therethrough into engagement with the track 12. The trunnion 21 of one of the roller retainers, preferably the roller retainer 15, is extended through an opening provided in the cover plate 23. An operating lever 29 is engaged

with the extending portion of the trunnion 21, the lower portion of said lever being retained against disengagement from the trunnion by means of overlapping flanges 30 and 31 provided 5 on the cover plate. The upper portion of the operating lever 29 is retained upon the door by virtue of the engagement between an offset finger 32 provided on the lever and a quadrant 33 secured to the door. Simultaneous movement of 10 the roller retainers 15 and 16 is obtained by means of a bar 34 connecting said retainers. Disengagement of the lower portion of the door from the track is prevented by means of the interlocking relationship between the hook shaped 15 portions 35 and 36 provided on the cover plates 23 and 24 and a depending flange 37 provided on the track 12.

When it is desired to move the door longitudinally it is only necessary to exert a downward pull upon the free end of the lever 29, whereupon the roller retainers 15 and 16 will rotate about the rollers 18 and 19 as fulcrums and will exert a lifting force upon the door about the points where the pairs of trunnions 21 and 25 22 are journaled in the door and in the cover plates. The weight of the doors is thus transferred to the rollers and the door may readily be moved longitudinally of the car.

While the form of lift mechanism illustrated 30 in the drawings has been described in some detail it is to be understood that any other form of lift mechanism may be utilized as well.

In the lowered or normal position of the door it is desirable that the weight thereof be transferred from the rollers directly to the supporting track. To this end frictional engagement 35 between the lower edge of the door and the track is had. This frictional engagement, in the instant embodiment of the invention occurs between 40 the track and the lower reinforcing angle 25 secured to the door.

In the considered embodiment of the invention the track 12 is provided with an upstanding portion 38, the upper surface of which lies above 45 the portion of the track engaged by the rollers 18 and 19 and which is preferably continuous with the length of the track. In its lowered position the angle member 25 has frictional engagement with the upstanding portion 38 and thus relieves the rollers 18 and 19 of the weight of the door. It will be apparent that by virtue of this 50 construction accumulation of dust, cinders or the like upon that portion of the track which is engaged by the rollers in the longitudinal movement of the door will not affect the proper seating of the lower edge of the door upon the upstanding portion 38 of the track. Moreover, the area presented by this upstanding portion for frictional engagement with the lower edge of the door has been substantially decreased so as to 55 materially decrease the possibility of cinders, dust or the like from adhering to the upper surface of the portion 38.

The principle of the invention described above is carried into the embodiments of the invention illustrated in Figures 5 and 7 of the drawings. In addition thereto these embodiments present a construction by means of which foreign substances will be prevented from being blown or drawn into the space between the door and the edge of the floor in the door opening and thence into the car.

In Figure 5 of the drawings the numeral 40 75 designates a threshold plate secured upon the

floor 41 of the car within the door opening. Securement of the threshold plate may be effected by means of bolts 42 extending through the threshold plate, the floor 41 and a horizontal leg 43 of an angle member 44 riveted to the side sill 13 by means of rivets 45. The threshold plate 40 is extended downwardly across the outer edge of the floor 41 and is then bent outwardly to provide a flange 46. Filler plates 47 are secured to the inwardly extending flange 48 of a supporting track 49 by means of rivets extending through said flange and the track supporting brackets 44. These filler plates extend under the outwardly directed flange 46 of the threshold plate to provide a support for said flange. The filler plates 47 and the flange 46 of the threshold plate provide a raised portion having an upper surface disposed above the upper surface of the track upon which the rollers of the lift mechanism are supported. The upper surface thus provided by the filler plates and the flange of the threshold plate is adapted to frictionally support the door in its lowered or normal position by frictionally engaging the reinforcing angle 50 provided upon the lower portion of the door.

In the embodiment of the invention illustrated in Figure 7 of the drawings a threshold plate 51 is utilized and is secured in the manner described in the consideration of the embodiment of the invention illustrated in Figure 5 of the drawings. The filler plate 51 is extended downwardly across the edge of the floor 41, and then bent outwardly to provide a flange 52 disposed in engagement with the inwardly directed flange 48 of the track 49. In this embodiment of the invention the filler plates 47 are omitted. In lieu thereof a reinforcing member 53 of the character shown in Figure 7 of the drawings is utilized. The member 53 is an angular member and embodies a vertical leg 54, by means of which said member is secured to the lower margin of the door and an outwardly directed horizontal leg 55. The vertical leg 54 of the reinforcing member 53 is extended downwardly below the horizontal leg 55 so as to provide a portion adapted to frictionally engage the flange 52 of the threshold plate 51 in order to support the door in its normal or lowered position.

It will be apparent that the embodiment of the invention illustrated in Figure 7 of the drawings, in common with the embodiment illustrated in Figure 5 of the drawings, provides a construction by means of which the ingress of foreign substances into the car through the space between the lower portion of the door and the floor is prohibited. Moreover, it will be apparent that in both of said modifications of the invention a materially decreased surface is presented for engagement with and frictional support of the door so as to substantially decrease the possibility of improper frictional support of the door in its lowered position.

A further embodiment of the invention is illustrated in Figure 6 of the drawings. A track 56 is utilized in this embodiment of the invention. The inwardly extending horizontal flange 57 thereof is formed with an upstanding portion 58 the upper surface of which lies above the tread of the track upon which the rollers 18 and 19 move. A reinforcing angle member 59 is secured to the lower margin of the door, said reinforcing member being provided with a downwardly and inwardly inclined flange 60 and a horizontal flange 61. In the lowered position of the door, as illustrated in Figure 6 of the draw- 75

ings, it is frictionally supported by means of the engagement between the upstanding portion 58 of the track and the horizontal flange 61 of the door reinforcing member 59. In the event that 5 during the lowering movement of the door such door be pulled outwardly away from the car side to the utmost extent permitted by the hook portions 35 and 36 provided on the cover plates 23 and 24 so as to provide a substantial distance between the inner face of the door and the threshold plate, such distance will be decreased by virtue of the engagement between the downwardly and inwardly extending flange 60 and the upstanding portion 58 of the track. In other 10 words, in the lowering movement the engagement between these parts will serve to force the door inwardly toward the car so as to avoid the existence of a large gap between the door and the threshold plate.

20 It will be apparent that numerous changes and modifications in the details of the invention will be clear to those skilled in the art. It is intended, therefore, that all such modifications and changes be comprehended within this invention, 25 which is to be limited only by the scope of the claims appended hereto.

I claim:

1. In a railway freight car having a door opening in a side thereof, a track secured to said car adjacent to the lower horizontal margin of said opening, a slidable door supported upon said track for closing said opening, means at least co-extensive with said margin of the door opening disposed vertically between said track and the lower edge of said door for continuously and frictionally supporting said door in the lowered and closed position thereof, thereby preventing cinders, dust and the like from passing below and across said door from the outside thereof and into said car through the door opening, said means being narrower than the lower edge of said door and means for supporting said door for movement upon said track when said frictional support is broken.

45 2. In a railway freight car having a door opening in a side thereof, a track secured to said car adjacent to the lower horizontal margin of said opening, a slidable lift door supported upon said track for closing said opening, a flange co-extensive with the length of said door carried thereby and depending below the lower edge of said door, said flange being narrower than said edge of the door and for its entire length being supported upon said track in the lowered 50 position of said door whereby to frictionally support said door and means for elevating and supporting said door for movement upon said track.

55 3. In a railway freight car having a door opening in a side thereof, a threshold plate secured to said car and extending across said opening, said plate being bent downwardly across the edge of said opening and then outwardly, a track secured to said car adjacent the lower horizontal margin of said opening, said outwardly bent portion being disposed upon said track, a lift door supported upon said track for closing said opening, said door having a flange co-extensive with the length thereof and depending therefrom, said depending flange continuously engaging said 60 outwardly bent portion of the threshold plate in the lowered position of said door to provide frictional support therefor, and means for elevating and supporting said door for movement upon said track.

70 4. In a railway freight car having a door open-

ing in a side thereof, a track secured to said car adjacent to the lower horizontal margin of said opening, a slidable door supported upon said track for closing said opening, said door comprising a reinforcing member secured to the lower margin of said door, said member having a leg extending substantially horizontally and in spaced vertical relation to said track, a flange substantially narrower than said leg and co-extensive with the length of said door depending therefrom, the lower edge of said flange being supported continuously by said track in the lowered position of said door whereby to frictionally support said door and means for elevating and supporting said door for movement upon said track.

5 5. In a railway house car having a door opening in a side thereof, a track secured to said car below said opening, a slidable door supported upon said track for closing said door opening 20 and a threshold plate secured to said car in said door opening, said plate extending downwardly into engagement with the tread of said track for the purpose set forth.

25 6. In a railway house car having a door opening in a side thereof, a track secured to said car below said opening, a slidable door supported upon said track for closing said door opening and a threshold plate secured to said car in said door opening, said plate extending downwardly 30 and having a flange supported by said track, said door being of the lift type and having frictional engagement with said threshold plate flange in the lowered position of said door, whereby said door is supported above said track and 35 means for elevating and supporting said door for movement upon said track.

7. In a railway freight car having a door opening in a side thereof, a track secured to said car adjacent to the lower horizontal margin of said opening, a slidable door supported upon said track for closing said opening, means interposed between and continuously engaging said track and said door to frictionally support said door in lowered and closed position in vertically spaced 40 relation to said track and means for elevating and supporting said door for anti-frictional movement upon said track.

45 8. In a railway freight car having a door opening in a side thereof, a track secured to said car adjacent to the lower horizontal margin of said opening, a slidable door supported upon said track for closing said opening, means interposed between and continuously engaging said track and the lower edge of said door to frictionally 50 support said door in lowered and closed position in vertically spaced relation to said track and means for elevating and supporting said door for anti-frictional movement upon said track.

55 9. In a railway freight car having a door opening in a side thereof, a track secured to said car adjacent to the lower horizontal margin of said opening, a slidable door supported upon said track for closing said opening, a longitudinally extending rib provided on said track continuously 60 engaging the lower edge of said door to frictionally support said door in lowered and closed position in vertically spaced relation to said track and means for elevating and supporting said door for anti-frictional movement upon said track.

65 10. In a railway freight car having a door opening in a side thereof, a track secured to said car adjacent to the lower horizontal margin of said opening, a slidable door supported upon said 70 track.

75

track for closing said opening, said door comprising a reinforcing member secured to the lower margin of said door, said member having a substantially horizontally extending leg, longitudinally extending means on said track continuously engaging a portion of said leg to frictionally sup-

port said door in lowered and closed position, thereby spacing the rest of said leg vertically above said track and means for elevating and supporting said door for anti-frictional movement upon said track.

GEORGE R. TREPTOW.
